UNITED STATES PATENT OFFICE.

JAMES H. TUDOR, OF LEXINGTON, KENTUCKY.

GATE.

SPECIFICATION forming part of Letters Patent No. 425,273, dated April 8, 1890.

Application filed January 2, 1890. Serial No. 335,658. (No model.)

To all whom it may concern:

Be it known that I, JAMES H. TUDOR, a citizen of the United States of America, residing at Lexington, in the county of Fayette and State of Kentucky, have invented certain new and useful Improvements in Gates, of which the following is a specification, reference being had therein to the accompanying drawings.

10 This invention pertains to certain new and useful improvements in gates, having for its object the provision of highly efficient means for easily opening and closing a gate.

15 The invention comprises a gate having a spring-held latch-rod, a pivoted keeper or retainer therefor, and a reel pivoted to the rear side of the hinging-post, connected with said rod, and operated from opposite sides of the gate, substantially as hereinafter fully set forth, and particularly pointed out in the claims.

20 In the accompanying drawings, Figure 1 is a view in perspective of my improved gate. Fig. 2 is an end elevation. Fig. 3 is an enlarged detail view of the latch keeper or retainer.

25 Referring to the drawings, A designates a gate, which at one end is provided with eyes a a, working on a vertical rod a', secured to post a². To the lower bar of the gate is secured one end of an inclined chain a³, the other end of which is secured to post a². This chain serves to raise the gate several inches in the opening thereof, and thereby prevents dragging or contact with any obstruction.

30 B is the latch-rod, and b a coil-spring encircling the same and secured at one end to gate A, its other end being connected to said rod. This rod is passed through an aperture of the 35 end bar C and a short guide-bar C', secured to the gate.

D is the latch keeper or retainer, consisting of an upper stationary arm or member d and a lower arm or member d', having an outer hooked end d² and fulcrumed on a lug d³ of arm d', and having a weight d⁴ pivotally secured to its inner end. The hooked end of arm d' is normally held in contact with arm d by said weight. The latch-rod B upon 40 striking between the ends of these arms d d'

will lower the outer end of the latter and be held between the lug d³ and hooked end d².

E is a reel composed of two bars e e', crossing each other at their centers, where they are pivotally secured to the rear side of hinging-post a². To opposite ends of bar e are secured the ends of operating cords or chains f f, which are carried in the same direction, but extended in opposite directions after engaging the forked ends f' of the reel-bars. 55 The operating-cords are passed over pulleys g g of posts g' g', and are provided with handle-bars g² at their ends. A cord or chain G, connected at one end to reel E, is passed around a roller or pulley g³ of a post G' in rear 60 of post a², and after being passed beneath a pulley g⁴ of gate A is connected to the end of the spring-held latch-rod B.

H is a hooked bar secured to a post h, and with it is designed to engage latch-rod B when 70 the gate is swung open. A slightly-bent spring h' is secured to this post, so as to give a slight initial movement to the gate in the closing thereof, the weight of the latter serving to complete its closing.

75 In practice an operator has only to pull on the end of either operating cord or chain, when, by the turning of the reel, the latch-rod will be disengaged from its keepers and the gate will swing around until said rod comes 80 in contact with hooked bar H, said gate being raised or elevated by the inclined rod a³. From the hooked bar said rod is released by again pulling on either cord, and the spring h', imparting an initial movement thereto, 85 will, with the elevation of the gate, cause the same readily to close. As the gate reaches post D' the latch-rod will lower the outer end of the movable arm or member of its keeper, and will be held in place by the return thereof 90 to its normal position.

95 From the foregoing description it will be seen that I have produced a gate extremely simple in construction, one that can be readily and easily opened and closed, and one that, comprising but few parts, will not readily get out of order.

The invention also embodies advantages in point of durability, general efficiency, and inexpensiveness.

I claim as my invention—

1. The combination, with the hinging-post, of the gate, the reel pivotally secured to the rear side of said post, the spring-held latch-rod secured to said gate, the keeper or retainer for said latch-rod, the cord or chain connected at one end to said reel and at its other end to said latch-rod, and the operating cords or chains connected to said reel, substantially as set forth.
2. The combination, with the hinging-post having the vertical rod, of the gate loosely secured on said rod, the reel pivoted to the rear side of said post, the spring-held latch-rod secured to said gate, the keeper or retainer for said latch-rod, the cord or chain connected at one end to said reel and at its other end to said latch-rod, the operating cords or chains

connected to said reel, and the inclined rod or chain connected at its ends to said gate and hinging-post, substantially as set forth.

3. The combination, with a swinging gate having a spring-held latch-rod, of the keeper or retainer comprising an upper stationary arm or member having a central depending lug and the lower movable arm or member fulcrumed on said lug and having its inner end weighted and its outer end hooked, substantially as set forth.

In testimony whereof I affix my signature in presence of two witnesses.

JAMES H. TUDOR.
